CARBURETOR

Ralph E. Gould, Los Angeles, Calif., assignor of
one-half to Newell N. Smith, Los Angeles,
Calif.

Application September 9, 1933, Serial No. 688,736

3 Claims. (Cl. 261—50)

This invention relates to and has for a primary object the provision of an improved type of carburetor embodying a mixing chamber for the reception of fuel under control, and a vacuum chamber adjacent thereto and offset from the air inlet in which a throttle valve is mounted and arranged for semi-automatic operation, and means connected with said vacuum chamber whereby suction from an internal combustion motor, to which the carburetor is attached, may be created in the vacuum chamber and the extent of the vacuum regulated for inducing the opening of the throttle valve in accordance with the varying requirements of the motor.

Another object is to provide in the mixing chamber an improved means of introducing the fuel and for thoroughly distributing the liquid fuel throughout the mixing chamber for mixture with air introduced thereto, said mixing means being controlled and automatically operable by and with the movement of the throttle valve.

A further object is to provide manually operable means for regulating and limiting the operation of the throttle valve rather than for automatically operating said valve whereby the valve may be opened by vacuum and the extent to which it is opened limited by the operation of said manually operable means, the closing of said throttle valve being under the control of the operator of the vehicle through the release of pressure on the accelerator.

Other and more detailed objects of invention may appear as the description progresses.

In the accompanying drawings I have shown a form of the invention in which the fuel feed mechanism is shown as separate from but connected with the carburetor. In said drawings,

Fig. 1 is a top plan view of the carburetor including connections for operating the throttle valve and for affording communication between the mixing chamber and the fuel feed apparatus.

Fig. 2 is a sectional elevation of the same on a medial longitudinal line.

Fig. 3 is a sectional plan on line 3—3 of Fig. 2 thru the mixing chamber.

Fig. 4 is a fragmentary sectional elevation of the fuel feed control valve mechanism on line 4—4 of Fig. 1.

Fig. 5 is a transverse section on line 5—5 of Fig. 3.

Fig. 6 is a fragmentary rear view of the carburetor showing the throttle valve control means.

Fig. 7 is a fragmentary section of the throttle valve and vacuum chamber showing means for

urging the throttle valve into closed position when the motor is decelerated.

Fig. 8 is a transverse section on line 8—8 of Fig. 2.

Briefly described, a carburetor embodying my improvements is preferably formed of an integral body member 1 with front and rear sides 2 and 3 in the form of sectors attached thereto, as by means of bolts or screws 4, 4 etc. The body 1 is provided with a vertical extension 5 of tubular form within which a mixing chamber 6 is provided and at the top of which a flange 7 is formed for attachment to the intake manifold of an internal combustion motor.

The lower portion of the body is segmental with a circular upper wall 8 forming a vacuum chamber 9 within which a throttle valve 10 is oscillatably mounted on a shaft 11, the outer wall 8 being concentric with the axis of said shaft and the throttle 10 having an arcuate upper web 12, the outer surface of which contacts with the inner surface 13 of the wall 8. Said throttle also has a radial web 14 which extends from the portion 12 inwardly to the hub 15 of the valve.

The lower portion of the mixing chamber 6 is arranged for communication with an air inlet chamber 16 formed in a tubular inlet member 17 attached to a portion of the body 18, as by means of screws 19. An opposite portion of the body is closed by means of a plate 20 held in position by screws 21, thereby closing the vacuum chamber 9 at the bottom of the body, while the web 14 of throttle valve 10 forms a closure for the opposite extremity of said chamber.

On the rear side of the carburetor adjacent the plate 3 a stop arm 22 is fixed to the end of shaft 11 and is provided with an inwardly bent lug or pin 23 which overlies a concentric portion 24 of an arm 25 to which the usual throttle operating rod 26 is attached for connecting the throttle with the accelerator lever or pedal in the driver's compartment of a vehicle. Thus as the rod 26 is moved forwardly by correspondingly depressing the accelerator lever or pedal the movement of the throttle valve 10 is limited by the engagement of the lug 23 with the arm 25, but a reverse movement of rod 26 and arm 25 would effect a corresponding reverse movement of throttle valve 10, as more fully explained hereinafter. The rearward movement of arm 25 is limited by means of a set screw 24' held in a lug 25' on plate 3 and adapted to adjustably engage a staple 23' on arm 25.

The vacuum chamber 9 is in communication with the mixing chamber 6 through the instru-

mentality of a tube 27 which has an inlet 28 to mixing chamber 6, and at its other end has a vacuum cylinder 29 connected therewith. The cylinder 29 is provided with a bore 30 in which a hollow piston 31 is reciprocably mounted and has an end closure 32 detachably held thereon. A tension spring 33 is carried internally of piston 31 and is connected at its outer end with an adjustment screw 34 and at its inner end with 10 a pin 35 threaded in the head of the piston and projecting therefrom.

The pin 35 slidably engages a reduced bore 36 in communication with tube 27, and bore 36 communicates with chamber 9 by means of a 15 passage 37 in the wall of cylinder 29 and continuing through a nipple 38 attached to said cylinder, as shown in Fig. 2. Thus suction from the mixing chamber 6 is applied thru tube 27 and cylinder 29 to the vacuum chamber 9, and communication between cylinder 29 and vacuum chamber 9 is regulated, as hereinafter described, by means of the piston 31.

A spray nozzle for the fuel is provided within the mixing chamber 6 and includes a base 39 which is diametrically positioned within chamber 6 and has a nipple 40 extended through an aperture 41 in the wall of said chamber. Said nipple 40 is centrally positioned within a boss 42 which is bored to receive the reduced inner end of a fitting 43 to which a fuel feed tube 44 is connected. Thus fuel from tube 44 is delivered to a chamber 45 in the fitting 43 and thence thru a strainer 46 and an inlet passage 47 formed in the base 39 from whence the fuel enters a central 30 chamber 48 in said base and is distributed, as hereinafter described.

The inner end of passage 47 forms a seat for a needle valve 49 which is adjustably mounted in an inclined bore 50 in the member 39. Said 40 valve is carried by a movable body member 51 which is slidably supported, as shown in Fig. 2, on one or more pins 52 outwardly extended from a boss 53 on extension 5. Said member 51 is bifurcated to provide inner and outer portions 54 and 55 respectively, and the portion 54 has a cylindrical extension 56 which slidably engages a bore 57 in the extension 5.

It will be noted that the needle valve 49 has a reduced stem 58 which extends into a cup-shaped 50 plug 59 which in turn is threaded into the portion 56 of member 51. The stem 58 has a head 60 at its inner extremity and between said head and the outer end of member 59 a compression spring 61 is mounted and tends to urge the valve 50 outwardly so that the head 60 is limited by engagement with the bottom of the socket within which the member 59 is mounted.

The outer furcation 55 of member 51 has a bore 62 which is closed at one end by means of 60 an externally headed screw 63, and a plunger 64 extends thru the opposite end of said bore and is provided within the bore with an enlarged head 65 and inwardly of said head with a reduced stem 66. The nut 63 is bored and threaded to 65 receive a smaller screw 67 and the screw 67 is bored at 68 to receive the outer end of stem 66. (See Fig. 4.)

A compression spring 69 is mounted conveniently within the bore 62 and may be interposed 70 as shown between a pair of collars 70 and 71 or between a corresponding extension from plunger 64 and the end of screw 67. The spring 69 thus serves to force the plunger to the left, as seen in Fig. 4, at which point the flange 65 75 will engage the bottom of the bore 62.

Below the member 51 a rock shaft 72 is mounted on the wall 8 of the housing member 1 in a pair of laterally spaced lugs 73 and 74. One end of said shaft 72 is bent downwardly at 75 and outwardly at 76 to form a pivot on which a lever 77 is swiveled. Intermediate the lugs 73 and 74 an arm 78 is fixedly mounted on shaft 72 and has a rounded upper end 79 which engages the outer end of plunger 64. Preferably the arm has an extension 80 which, when the plunger 64 is in 10 the position shown in Fig. 4, engages a shoulder 81 on member 51 for limiting the movement of arm 78 in a counter-clockwise direction and preventing the dislodgement of the assembled valve body and mechanism from normally operative 15 position on the housing 1.

The lever 77 has oppositely extended arms 82 and 83, the lowermost of which (arm 83) operatively engages a cam 84 which is fixed to shaft 11 externally of the cover plate 2. Said cam has 20 an elongated eccentric dwell 85, a shorter dwell 86, and a projection 87 formed on its periphery, as shown in Fig. 2. When the motor is inoperative and the throttle valve 10 is in closed position with the web 14 thereof substantially below the position shown in Fig. 2, the lower extremity of arm 83 will rest upon the dwell or projection 87 of the cam. Under such a condition the needle valve 50 will be entirely closed and the member 51 will be thrust inwardly to 30 a maximum extent thru its connection with arm 78 and by reason of the tension of spring 88 which is carried on and serves to tension shaft 72, as shown in Fig. 1.

When the motor is started and the throttle valve is in idling position substantially as shown in Fig. 2, the lower end of arm 83 will engage the short dwell 86 of cam 84 and the valve body 51 will be slightly projected from engagement with the boss 53 to an extent sufficient to slightly open 40 the needle valve 50, thereby supplying sufficient fuel thru inlet 47 for operating the motor at idling speed.

As the motor is accelerated arm 83 is elevated from the dwell 86 to and gradually traverses the 45 ascending dwell 85 on cam 84, thereby gradually extending the valve body 51 outwardly and correspondingly opening needle valve 50. The mixture of air and fuel is controlled by means of an adjustable arm 89 which is pivotally mounted on 50 a rock shaft 90 carried in lugs 91, 91 on member 1, and at one end said shaft has an arm 92 fixed thereto for connection with a rod 93 leading to the driver's compartment of a vehicle and to the instrument board for manual operation and adjustment of the arm 89.

Said arm 89 underlies the arm 82 of lever 77 and the lower surface 94 of arm 82 is curved so that when throttle valve 10 is in idling position and lever 77 is correspondingly positioned relative to its cam 84 the surface 94 will be concentric with the axis of arm 90. The upper extremity 95 of arm 82, however, is eccentric with respect to the axis of arm 89 so that when starting the motor for the purpose of richening the 65 fuel mixture the rod 93 may be pulled forwardly, thereby correspondingly elevating arm 89 and moving the same into contact with the eccentric portion 95 of arm 82, which adjustment serves to project the member 51 outwardly and open 70 needle valve 50.

When the motor is started and is operated at idling speed the rod 93 may be retracted manually or by means of a suitable spring for restoring arm 89 to the position shown in Fig. 2. 75

Throttle valve 10 is urged into closing position by means of a spring 96 which is wound around a pin extended through plates 2 and 3, and has a portion 96' thereof engaging an arm 97 which is detachably held at its inner end on the hub 98 of valve 10.

From the foregoing description it will be noted that the vacuum in chamber 9 tends to open throttle valve 10 and accelerate the speed of the 10 motor and that the opening of said throttle valve is accomplished against the tension of the spring 96. The spray nozzle in the mixing chamber is centrally mounted on the base 39 and includes a circular body 99 having a conical portion 100 which is slightly smaller than and seats in a 15 conical opening 101 on the upper side of member 39 above the chamber 48.

Intermediate the outlet 100 and the chamber 48 the member 39 is internally threaded to receive the lower externally threaded end 102 of the member 99. Communication between chamber 48 and outlet 100 is established by means of a plurality of radial slots 103 which are formed in the portion 102 of member 99. Thus the fuel 25 from the inlet 47 is directed upwardly thru passage 48, slots 103 and the annular outlet 101 into that portion of chamber 6 which is above the member 39. Above the outlet 101, however, I provide a distributor 104 which has a plurality of preferably pointed projections 105, as shown in Figs. 1 and 2. Said distributor is held in position on the member 99 by means of a nut 106 into which a screw 107 is threaded, said screw being extended through the member 99 with its 30 head at the bottom thereof, as shown in Fig. 2.

The purpose of the distributor 104 is to deflect portions of the jet of fuel from the annular outlet 101 into the outer portion of chamber 6 so as to thoroughly atomize the fuel for complete 40 mixture with the air which enters through the air tube 17 around the member 39 in passage 6.

I have shown in Fig. 2 a downwardly inclined passage 107 in member 39 which communicates with a tube 108 leading to a recess 109 within 45 the lower portion of the throttle valve chamber and which serves as a scavenger for fuel from chamber 48, particularly when the engine is operating at an idling speed. At idling speed the air velocity through the mixing chamber 6 is 50 very low, thereby permitting the draining of liquid fuel from chamber 48 to a lower point of higher velocity. Under such conditions fuel thus drained will flow downwardly thru passage 107 and tube 108 into recess 109, where it will be 55 siphoned from the tube by the inflow of air through the air inlet 17.

As the motor is accelerated the need for the scavenging tube 108 becomes gradually less until a point is reached in the operation of the motor 60 when all of the fuel so introduced into chamber 48 is completely and properly vaporized and mixed with the air at the nozzle in chamber 6, due to the greater air velocity at this point.

A certain amount of air may be drawn thru 65 tube 108 into the lower portion of chamber 48, thereby facilitating the mixing and vaporization of the fuel. The tube 108 thus serves the purpose of diverting liquid fuel from the bottom of chamber 48 to the air inlet when the carburetor 70 is changed from a high to a lower engine speed.

I call particular attention to two important features of my carburetor. First: The throttle valve 10 is located below rather than above the fuel nozzle, as in other types of carburetors, and 75 said throttle valve instead of being centrally

mounted in the mixing chamber, has an axis offset from the axis of the air inlet and the mixing chamber. Second: I provide the vacuum chamber 9 at the rear of the throttle valve and therefore offset from the air passage and the 5 mixing chamber, and the area of the vacuum chamber varies with the opening and closing of the throttle.

As shown in Fig. 7, the application of the spring 96 to the throttle 10 is such that as the throttle 10 valve is rotated in a clockwise direction, i. e., when the valve is being opened, the fulcrum 97 of the arm 97 will gradually approach a dead center position with respect to the axis of shaft 11 and the point 98 on arm 97 at which the portion 15 96' of spring 96 is connected. Accordingly the effect of the spring 96 on the throttle is gradually reduced. As the throttle is moved to closing position the effect of spring 96 is gradually increased, thus insuring the positive closing of 20 the throttle.

Incidentally, when the throttle 10 is in closed position the lower side of the web 14 rests upon a lug 13' extended inwardly in the bottom of the end 18 of the housing. When the throttle is 25 completely open the rear edge of the arcuate portion 12 thereof will engage the inner side of the closure plate 20.

In operation, when the several elements of the 30 carburetor are adjusted substantially as shown in Fig. 2 with a rod 26 connected with the accelerator pedal, the motor is started in the usual way by adjusting the arm 89 relative to lever 77, which operation is accomplished by pulling on the rod 93, as in an ordinary choke device. 35 As hereinbefore described the movement of the arm 89 upwardly on the edge 94 of lever 77 changes the fulcrum for said lever so that the operation of needle valve 49 is open to a sufficient extent to richen the fuel for a starting operation. 40

The rod 26 is subject to the tension of a spring (not shown) which is usually connected with the accelerator pedal or throttle lever and serves the purpose of restoring the rod 26 to normal position. The connection of rod 26 with throttle 45 valve 10 thus places the movement of the throttle valve under control of the operator, said valve being limited as to its opening movement by the position of rod 26 and arm 25 which are under control of the operator. 50

It will be understood that the rod 26 in no case serves to open the throttle valve, the opening of 55 said valve being accomplished entirely thru vacuum in chamber 9 and the extent of its opening limited by rod 26. Throttle valve 10 serves a dual purpose of closing the air inlet 17 and the mixing chamber 6 against communication with vacuum chamber 9, the wall 14 serving the first mentioned purpose and the arcuate wall 12 serving the latter purpose. 60

With the motor operating at idling speed the lower end of lever 77 is positioned as shown in Fig. 2 on the short dwell 86 of cam 84, and as the motor is accelerated the throttle valve 10 is gradually opened by the vacuum in chamber 9, whereupon the lower end of lever 77 will gradually traverse the ascending dwell 85 on the cam, thereby opening the needle valve 49 to meet the gradually increasing requirements of the motor. The 65 volume of fuel delivered thru inlet 47 to chamber 48 is increased above a normal flow so long as arm 89 is adjusted from its lowermost position shown in Fig. 2 to any upper position. Said arm 89 provides a variable fulcrum for the lever 77 and causes the supply of an abnormal quantity 70 75

of fuel as long as it is adjusted from its normal position.

The regulator 29 serves to maintain a substantially uniform degree of vacuum in the chamber 9 for gradually opening the throttle valve 10 as the motor is accelerated. When an unusual quantity of fuel is desired as when starting a motor, arm 89 may be adjusted so as to engage a portion 95' near the extremity 95 of lever 77 so that the needle valve 49 will be correspondingly opened to a greater extent than normally.

At starting position the lower end of lever 77 is engaged by the short dwell 87, and all tension on the needle valve is relieved. The fuel delivered to chamber 45 is transmitted to chamber 48 from which it is sprayed upwardly beneath the distributor 104 and thoroughly atomized for mixture with the air delivered thru inlet 17.

The purpose of regulator 29 is to limit the degree of vacuum at all times in chamber 9 to a substantially uniform extent so that upon the release of rod 26 the throttle valve 10 will be free to close by the tension of spring 96. The tension of spring 96 on throttle valve 10 gradually increases as the throttle valve is closed from a completely open position and is at a maximum when the valve is closed.

The throttle valve 10 being disposed in the vacuum chamber 9 and forming one of the closures therefor varies the cross sectional area of said chamber as the valve is moved to or from closed position, but the suction in said chamber is not varied by the movement of the throttle valve.

The position of the throttle valve below the atomizing nozzle effects the atomization of the fuel in a vacuum rather than at atmospheric pressure in the case of an atomizer located below the throttle valve, as in ordinary carburetors.

It will be observed that I have provided a novel carburetor with a vacuum chamber offset from the path of the air thru the carburetor in which the throttle valve is rotatable mounted and serves to prevent communication between the air passage and said chamber; a fuel control valve for regulating the inflow of fuel to the mixing chamber, and means under the control of the throttle valve for regulating the opening of said inlet valve.

What I claim is:

50 1. A carburetor comprising a housing having a

mixing chamber therein with an air inlet, a vacuum chamber offset from said mixing chamber, a throttle valve rotatably mounted in said vacuum chamber and forming a closure against communication between said mixing chamber and said air inlet and said vacuum chamber, said mixing chamber having a fuel inlet, a spray nozzle centrally mounted in said chamber, means on said nozzle for deflecting and distributing the fuel thruout the area of said mixing chamber for 10 mixture with the air from said air inlet, a fuel control valve for regulating the flow of fuel through said inlet to said nozzle, and means for operatively connecting said control valve with said throttle valve for automatically opening said 15 control valve to correspond to the opening movement of said throttle valve.

2. A carburetor comprising a housing having a passage therethrough and forming a mixing chamber at one end and an air inlet at the other 20 end of said passage, an extension having a recess at one side of said housing having a cross section of a sector, the axis of which is substantially alined with a point on the periphery of said passage, a throttle valve pivotally mounted in said 25 housing coaxially with said extension at a point below the opening between said air inlet and said mixing chamber and formed with connecting radial and arcuate walls, said radial wall adapted to completely overlie said opening for regulating 30 communication between said air inlet and said mixing chamber and said arcuate wall adapted to prevent communication between said mixing chamber and the recess in said extension, for the 35 purpose described.

3. A carburetor comprising a housing provided with a passage therethrough and an extension on said housing having a chamber offset from said passage, a throttle valve pivotally mounted 40 on said housing on an axis offset from the axis of said passage, said valve having a radial wall and a connecting arcuate wall, said radial wall adapted to regulate communication between the opposite portions of said passage, said arcuate wall 45 adapted to completely close said passage when disposed transversely so as to prevent communication between said passage and the chamber in said extension, for the purpose described.

RALPH E. GOULD. 50
